RECORD CONTAINER

Herbert Goldich, Springfield, Mass., assignor of
one-half to J. Clayton Flax, Springfield, Mass.

Application October 25, 1944, Serial No. 560,327

1 Claim. (Cl. 312—10)

1

This invention relates to improvements in containers for phonograph records or the like.

The invention may be incorporated into a phonograph cabinet or it may be, and preferably is, used separately in place of the usual record album of the type that has hinged leaves with record pockets therein.

The invention has for its general object to provide a record container which is simple in construction, cheap to manufacture and compact and which provides for the automatic projection of the records partially out of the container, when the cover of the container is opened, whereby the records may be conveniently selected.

The invention has for another object to provide a record container in the form of a simple box with a plurality of partitions therein to form record compartments together with spacing pieces between adjacent partitions, some of which pieces form forwardly sloping floors, one for each of the record compartments, and some of which form stops, one for each of the record compartments, to limit the forward rolling movement of the records, when the cover is open.

The invention has for another object the provision in a record container of the class described of a plurality of partitions which are free to move laterally toward or away from one another adjacent their front and upper portions for the purpose of enabling the partitions to be manually spread apart to facilitate insertion of the records into the compartments and to avoid binding of the records and partitions in case either the partitions or the records are warped.

The invention will be disclosed with reference to the accompanying drawing in which—

Fig. 1 is a sectional elevational view of the record container with the cover closed;

Fig. 2 is a similar view with the cover shown open and partly broken away;

Figs. 3, 4 and 5 are sectional views taken on the lines 3—3, 4—4 and 5—5 of Fig. 2 and drawn to a larger scale;

Figs. 6 and 7 are small scale perspective views of the partitions used in the container, and

Fig. 8 is a perspective view of a modified form of partition.

Referring to the drawing; the record container includes a box-like receptacle of any suitable material having parallel side walls 1 and 2, parallel top and bottom walls 3 and 4, respectively, and parallel back and front walls 5 and 6. The front wall 6 forms a cover and is hinged to the bottom wall 4 in any suitable manner, as for example by the strap 7. The cover 6 may be releasably held

2

in closed position by any suitable fastening means and, as herein shown, is provided with a snap fastener element 8 to be engaged by a mating fastener element 9, carried on the free end of a strap 10, which is secured to the inner face of top wall 3.

The container described is divided off into a plurality (twelve as shown) of record-holding compartments by a plurality of partitions 11 and 12. Each of these partitions is rectangular and of thin section. As shown each partition is of slightly less area than the side wall 1 or 2 and it abuts the bottom wall 4 and back wall 5 but is spaced from the top wall 3 and cover 6. The partitions may be made of cardboard or any other suitable material. To provide for twelve record compartments 13, eleven of the partitions are used—six partitions 11 and five partitions 12, in alternating arrangement. Adjacent side wall 1 is a partition 11 and adjacent side wall 2 is a partition 11, thus forming the two end compartments 13 of the series. The remaining compartments are each formed between a partition 11 and partition 12.

At the bottom of each compartment 13 is a triangular piece 14 which abuts rear wall 5 and bottom wall 4 and extends forwardly from the rear wall over about two-thirds of the bottom wall. This piece 14 provides a sloping floor for the record compartment. At the front and lower corner of each compartment 13 is a stop piece 15, which limits the extent to which a record 16 can roll forwardly when cover 6 is opened, as will be clear from Fig. 2. In the rear upper portion of each compartment 13 is a spacer 17. The pieces 14, 15 and 17 are fixed to and on opposite sides of each partition 11. The partitions 12 carry no such pieces. The series of six partitions 11 and five partitions 12, when assembled in a stack, are thrust into the container and closely fit between the side walls 1 and 2, being held in place by frictional engagement.

An alternative arrangement consists in using ten partitions, such as 11' (Fig. 8), which have the pieces 14, 15 and 17 fixed on only one side thereof, and then to use a single partition 11 as an end member of the series.

A small strip 18 is suitably fixed in the lower front portion of the container, covering up the front ends of all the pieces 15 and bearing a series of consecutive numbers, such as 1 to 12, or any other desired designations, for the twelve record compartments 13. On the cover 6, an index 19 may be provided, showing the records located in each compartment.

The operation will be clear from Figs. 1 and 2. The records 16 rest on the forwardly sloping floors provided by the pieces 14 and roll forwardly until they rest against the closed cover 6. When this cover is opened, all of the records roll forwardly until they are arrested by the stops 15. The records are then projected partially out of the container, as shown in Fig. 2, so that they may be readily grasped. The cover 6 will lie flat against the table, on which the container is supported, and expose the index 19. Having found from this index the compartment in which the desired record is located, one selects from proper numbered compartment, the desired record. When a record is to be replaced, the two partitions 11 and 12, which form the sides of the desired record compartment 13, are manually spread apart enough so that the record 16 may easily be inserted into the compartment. The upper front corners of the partitions are preferably unsecured, as shown, to enable the partitions to be spread apart for the above purpose. It is also desirable not to have these partitions rigidly fixed for the reason that the records are sometimes warped and yielding of the partitions laterally is required to avoid binding. Also, the partitions themselves may warp and it is therefore desirable that they be free to yield laterally if and when required. It is also preferable to have these partitions terminate far enough below the top wall of the container so that one may gain access to their upper edges for the purpose of spreading them apart when necessary.

The invention provides a record container which is simple in construction and capable of being manufactured in quantities at low unit cost. The container is simply a box with a hinged cover and a fastener. The partitions are simple rectangular pieces of cardboard with the floor pieces, stop pieces and spacer pieces attached thereto, as by gluing. These partitions, when as-

sembled into a stack are simply thrust into the container and are thereafter held in place by frictional engagement. The container is compact and its volume is not very much greater than that of the twelve records plus the necessary thin separators such as the partitions 11 and 12. The construction nevertheless provides for the automatic projection of the records, caused by opening the cover, to enable convenience in selecting the records.

What I claim is:

A container for records or the like, comprising, a box having a bottom, a top, upstanding parallel side walls, and upstanding front and back walls, 15 the front wall forming a cover movable to open or close the container, a plurality of partitions of resilient material within the container paralleling the side walls and forming between them and between the end partitions and said side 20 walls a plurality of record compartments, and spacing pieces between adjacent partitions and between the end partitions and the side walls, some of said pieces forming floors one for each compartment and sloping forwardly and down- 25 wardly toward the cover, the cover being so disposed when closed as to hold all the records in a retracted position, other of said pieces forming stops one for each compartment near the lower front portion thereof to limit the forward 30 rolling of the records down said floors when the cover is opened, said partitions and spacing pieces abutting one another and closely fitting between the side walls so as to be held in place by frictional engagement, said partitions termin- 35 ating short of the top wall and being free for lateral movement at their upper front corners, whereby they may be spread apart to enable easy insertion of records and whereby they may yield when required if the records or partitions 40 are warped.

HERBERT GOLDICH.
